UNITED STATES PATENT OFFICE.

GEORGE P. FINDLAY, GEORGE D. LOCKWOOD, AND JOHN G. SODERBERG, OF WORCESTER, MASSACHUSETTS, ASSIGNEES TO CROMPTON & KNOWLES LOOM WORKS, A CORPORATION OF MASSACHUSETTS.

YARN-TUBE FRAME.

Application filed May 3, 1922. Serial No. 558,153.

To all whom it may concern:

Be it known that we, GEORGE P. FINDLAY, GEORGE D. LOCKWOOD, and JOHN G. SODERBERG, citizens of the United States, all residing at Worcester, in the county of Worcester and State of Massachusetts, have invented a new and useful Yarn-Tube Frame, of which the following is a specification.

This invention relates to yarn tube frames 10 as used in looms and particularly in Axminster carpet looms. Such looms are now built of much greater width than was formerly the practice and the tube frames are of correspondingly increased length, 15 each frame now containing a very large number of individual yarn tubes. Several hundred of these tube frames may be required to equip a single carpet loom, making the tube frames by far the largest and most 20 expensive accessory of the loom.

It is the general object of our invention to improve such yarn tube frames in numerous details of construction by which the tube is mechanically perfected while at the same 25 time its cost of manufacture is materially reduced.

One of the specific objects of our invention is to provide an improved construction by which sections of yarn tubes may be secured to a tubular frame member without the use of solder or brazing and in such a 30 way that a section may be readily removed and replaced in case of accident thereto.

Another feature of our invention relates 35 to the provision of means for preventing yarn from being caught between the ends of adjacent tube sections.

Our invention further relates to arrangements and combinations of parts which will 40 be hereinafter described and more particularly pointed out in the appended claims.

A preferred form of our invention is shown in the drawings in which—

Fig. 1 is a front elevation of one of our 45 improved tube frames;

Fig. 2 is a transverse sectional elevation, taken along the line 2—2 in Fig 1;

Fig. 3 is a front elevation of the tube frame with the yarn tubes removed and is 50 taken substantially along the line 3—3 in Fig. 2;

Fig. 4 is a detail sectional view of means for fastening the tube sections to the tube frame, taken along the line 4—4 in Fig. 1;

Fig. 5 is a detail front elevation showing 55 the means for bridging the space between adjacent tube sections; and

Fig. 6 is a detail sectional view, taken along the line 6—6 in Fig. 5.

Referring to the drawings, we have shown 60 a tube frame comprising a rectangular metal tubular member 10 having walls of substantial thickness and extending the full length of the frame. Brackets 11 are secured to the tube 10 at the ends thereof and intermediate brackets or bearings 12 are fastened to the upper surface thereof, said brackets and bearings supporting the yarn spool or spools 13 from which the yarn is delivered to the yarn tubes. The brackets 65 11 cover and tightly close the ends of the tubular member 10 and may be secured therein by screws 14 (Fig. 3).

The interior of the tubular member 10 is 70 preferably provided with a relatively soft 75 filler, such as the wedge-shaped strips of soft wood indicated at 15. Our invention is not limited to a specific form and arrangement of the soft filler but a convenient construction involves the use of a pair of 80 tapered outer strips and a double tapered center strip which may be driven between the outer strips to seat them firmly in the tubular member 10.

After the strips are inserted, the brackets 85 11 may be secured in place, closing the ends of the member 10 and holding the strips from displacement. The upper and lower strips are suitably recessed to admit entrance of the inwardly extending arms 16 of the 90 brackets.

The yarn tubes 17 may be of the usual construction and are preferably assembled in sections by soldering or otherwise securing them to relatively thin metal plates 18. 95 As shown in the drawings, these plates 18 are of angular section and each plate is bent outward at 19 to form a rib or corrugation extending lengthwise of the strip and adjacent the upper ends of the yarn tubes 100 17. This rib supports the yarn and prevents contact thereof with the sharp upper edges of the yarn tubes.

The plates 18 are preferably made in relatively short lengths and may be firmly secured to the tube frame by screws 20 passing through openings in the plates 18 and also through corresponding openings 21 in

the tubular member 10. The screws are firmly held in the relatively soft wood filler and retain the sections of yarn tubes securely in position.

5 The screw openings 21 in the member 10 are preferably countersunk and the screws 20 are also preferably of the countersunk head type, so that the screws will draw the relatively thin metal of the plates 18 into 10 the countersunk openings as shown in Fig. 4.

This method of attachment has two important advantages. The tubes are firmly held from lateral displacement by the inwardly projecting portions of the tube 15 plates and furthermore the screw openings in the member 10 are effectually sealed, preventing the entrance of air or moisture which might injuriously affect the wood filler.

It is found in practice to be very difficult 20 to obtain absolutely close fitting joints between the tube sections or plates 18 and where spaces occur, there is a possibility of the yarn being caught on the edges of the plates. To reduce this possibility, we form 25 a projection 21' on one end of each plate 18, said projection being adapted to fit under the rib or corrugation 19 on an adjacent section as shown in Figs. 5 and 6. This construction bridges across the space between 30 adjacent sections and effectually prevents the catching of the yarn between the edges of the plates.

It has been heretofore customary to secure the yarn tubes 17 or their plates 18 to 35 the tube frame by soldering them thereto. It has been found, however, that the heat of this soldering operation seriously distorts or warps the present long tube frames to such an extent that one and sometimes 40 two straightening operations are necessary to restore the frames to usable condition. This warping of the frames is entirely avoided by our improved construction in which there is no soldering or other application of heat to the member 10 at any stage 45 in the construction of the tube frame, the tubes 17 being soldered to the plates 18 while the plates are entirely separate from the member 10. This method of construction 50 also avoids the possibility of overheating and possibly igniting the fillers 15 within the tube 10. The omission of the soldering also improves the appearance of the frames, as the tubular members are not rusted or discolored by soldering paste or acid. The cost is also reduced, as the outside of 55 the tubular members may have a less expensive finish when there is no acid to resist, and injury of yarn by rust and acid is avoided. Soldering also involved additional labor in scraping and smoothing the parts after soldering and in clearing the narrow slots between the tubes.

We have already referred to the possibility 60 of convenient removal and replace-

ment of a single section of tube in case of accident to one or more of the tubes contained therein.

Having thus described our invention and certain advantages thereof, it will be evident that changes and modifications can be made in our invention within the spirit and scope thereof as set forth in the claims, and we do not wish to be otherwise limited to the details herein disclosed, but what we 75 claim is:—

1. A yarn tube frame comprising a tubular metal frame member, a relatively soft filler within said member, a plurality of 80 yarn tubes, a plate to which a series of said tubes are secured, said plate and frame member having aligned spaced transverse openings therein, and fastening devices extending freely through said openings and having holding engagement in the soft filler 85 within said frame member.

2. A yarn tube frame comprising a relatively long frame member, a series of relatively short plates mounted on the frame 90 member, a plurality of yarn tubes secured in relatively small groups to said plates, and means to bridge the space between the ends of adjacent plates and thus prevent the lodging of the yarn in said space.

3. A yarn tube frame comprising a metallic tubular shell extending throughout the length of the frame, a filler of softer material, a plurality of yarn tubes assembled in a plurality of separate relatively small 100 groups and fastening means extending transversely of said shell for securing the separate groups to the metallic shell and for permitting convenient removal thereof, said fastening means freely passing through the metallic shell and being embedded in holding engagement in the relatively soft material of the filler.

4. A yarn tube frame comprising a tubular member and a plurality of plates secured thereto and having yarn tubes mounted 110 thereon, said plates being formed in relatively short sections and said plates having means integral therewith to bridge the space between the pairs of adjacent plates.

5. A yarn tube frame comprising a tubular member, a series of plates secured thereto and each having a plurality of yarn tubes mounted thereon, said plates each having a corrugation adjacent the upper ends of the 115 yarn tubes and being formed in relatively short sections, each plate having a projection at one end extending under the corrugated part of the next adjacent plate and bridging the space between said plates.

6. A yarn tube frame comprising a rectangular tubular member, a soft filler for 120 said member comprising reversely disposed tapered wood strips fitted within said member, a plurality of yarn tubes, and means to secure said tubes to said member, said means 125 130

comprising fastening devices extending through said tubular member and fixed in said wood strips.

7. A yarn tube frame comprising a rectangular tubular member, a soft filler for said member comprising reversely disposed tapered wood strips fitted within said member, a plurality of yarn tubes, and means to secure said tubes to said member, said means comprising fastening devices extending through said tubular member and entering said filler from two adjacent sides of said member.

8. A yarn tube frame comprising a rectangular tubular member, a soft filler for said member comprising reversely disposed tapered wood strips fitted within said member, a plurality of yarn tubes, and means to secure said tubes to said member, said means comprising fastening devices extending through said tubular member and entering said filler from two adjacent sides of said member and certain of said fastening devices extending into more than one filler strip and preventing longitudinal displacement thereof.

9. A yarn tube frame comprising a metal tubular member with walls of substantial thickness, a plurality of yarn tubes, a series of plates to which said tubes are secured in relatively small groups, and fastening devices extending transversely through said plates and tubular member and secured therein.

10. A yarn tube frame comprising a metal tubular member with walls of substantial thickness, a plurality of yarn tubes, a series of plates to which said tubes are permanently secured in relatively small groups, and fastening devices extending through said plates and tubular member and secured therein, said member having countersunk openings and said plates having portions displaced into said openings by said fastening devices and being thereby held from lateral displacement.

In testimony whereof we have hereunto affixed our signatures.

GEORGE P. FINDLAY.
